UNITED STATES PATENT OFFICE.

THOMAS H. RANEY, OF AURORA, LOUISIANA.

DESIGN FOR A CULTIVATOR-SHOVEL.

SPECIFICATION forming part of Design No. 28,034, dated December 14, 1897.

Application filed October 30, 1897. Serial No. 656,971. Term of patent 14 years.

To all whom it may concern:

Be it known that I, THOMAS H. RANEY, a citizen of the United States, residing at Aurora, in the parish of Washington and State 5 of Louisiana, have invented and produced a certain new and original Design for Cultivator-Shovels; and I do declare the following to be a full, clear, and exact description of the invention, such as will enable others skilled 10 in the art to which it appertains to make and use the same.

My invention has relation to a new and original design for a cultivator-shovel; and it consists of a shovel of the configuration shown in 15 the accompanying drawings, in which—

Figure 1 is a plan view of my design. Fig. 2 is an edge view; and Fig. 3 is a cross-sectional view on line $x x$, Fig. 1.

The leading features of my design comprise

a body portion 1, having parallel edges 2, inclined edges 3, terminating in a point 4, and outwardly and laterally curved horns 5, terminating in angular points 6. The horns are curved outwardly, as shown in Fig. 2, and the plate is provided with a longitudinal central 20 bulge, as shown in Fig. 3, and the plate at the junction of the parallel sides with the inclined 25 edge is bent outwardly, as shown at 7 in Fig. 2.

What I claim is—

The design for a cultivator-shovel, as herein 30 shown and described.

In testimony whereof I hereunto affix my signature in presence of two witnesses.

THOMAS H. RANEY.

Witnesses:

JOHN R. PASMAN,
W. J. JONES.
